UNITED STATES PATENT OFFICE.

WILLIAM HENRY DAVIS, OF BAYONNE, NEW JERSEY, ASSIGNOR TO EUREKA FIRE HOSE MANUFACTURING COMPANY, OF JERSEY CITY, NEW JERSEY.

EXPANDER.

1,068,860.

Specification of Letters Patent.

Patented July 29, 1913.

Application filed April 4, 1913. Serial No. 758,909.

To all whom it may concern:

Be it known that I, WILLIAM HENRY DAVIS, of Bayonne, in the county of Hudson and State of New Jersey, have invented a new and useful Improvement in Expanders, of which the following is a specification.

My invention relates to expanders for expanding the holding ring used in fastening couplings upon hydraulic or other hose. The invention is applicable to all forms of expanders of this kind whether operated by power or by hand. Expanders of the kind in question are provided with segments held together elastically around a mandrel having a tapered or frusto-conical front portion, which when moved lengthwise in the proper direction will expand the segments which encircle it, and will thus effect in a well known manner the expansion of the copper or brass holding ring previously placed on such segments into the hose coupling surrounding it, the body of the hose being clamped between the body of the coupling and the holding ring and being thus secured tightly to the coupling. After the operation is completed the mandrel is moved in the opposite direction with a view to withdrawing the expanding conical portion of it from the segments. But owing to the tight wedging together of the segments and the mandrel, the segments with the coupling carried by them will move with the mandrel and remain jammed tightly thereon unless restrained in some way. A usual method of restraining the lengthwise movement of the segments has been to cause them to engage at their rear ends with the body of the bearing in which the mandrel moves, being provided, for example, with hooked rear ends which engage an annular retaining recess or slot in the front end of the mandrel bearing. Restraining devices of this character serve well enough so long as they are in order, but it frequently happens in the use of the machine that the segments become misplaced or jammed, and in such case the retaining devices have no useful purpose, but serve only to distort the stand and mandrel bearing in the same, or to otherwise injure the machine. Other modes of preventing segments or couplings from moving forward with the mandrel while not open, at least to the same extent, to the serious objection above noted, are none the less defective in that they require very considerable

manipulation and adjustment in order to adapt them to varying sizes and conditions of hose.

The purpose of my invention is to obviate all these objections, and to provide an improved device which may be used with equal facility upon all sizes and forms of couplings, and by inexpert labor, without risk of injury either to the mechanism or to the hose.

I will first describe my improvement in connection with the accompanying drawings forming part of this specification, and will then point it out more particularly in the claim.

In the drawings—Figure 1 is a side elevation of an expander embodying my improvement showing the hose coupling on the expander and held in place in accordance with my invention. Fig. 2 is a longitudinal horizontal axial section of the implement showing the holding chain in place. Fig. 3 is a section on line 3—3 Fig. 1. Fig. 4 is a section on line 4—4 Fig. 1. Fig. 5 is a perspective view of one of the segments detached.

A is the stand of the implement, adapted to be secured to a bench or other convenient support. In the top of the stand is the horizontal tubular bearing A' for reception of the mandrel, having an interior of polygonal cross section for a portion of its length, as at a, and at its rear end a nut B swiveled in the stand concentric with the bore of the tubular bearing, and provided with radial handles B' by which it may be rotated to advance or retract the mandrel. The mandrel C is provided with a front conical or frusto-conical portion c constituting the expander proper, an intermediate portion c' of polygonal cross section to fit and slide lengthwise without rotation in the portion a of the tubular bearing A', and a rear portion formed as a screw threaded spindle c² which passes through and engages the swiveled nut B. Upon the mandrel, in advance of the front end of the tubular bearing A', are mounted the expander segments D, having their front ends notched as shown to form when assembled an annular groove to receive a rubber or other elastic ring d, by which the segments are held together on the mandrel. The working faces of the segment are of a length equal to that of the copper coupling ring to.

be expanded. Rotation of the swiveled nut B in one direction will retract the mandrel C, with the effect of expanding the segments and consequently the copper coupling ring which surrounds them. Rotation of the nut in the opposite direction will permit the segments to draw together and to relieve the copper coupling of pressure.

The parts thus far described are constructed and combined together for operation in a manner usual in expanders for hose couplings, save perhaps that the segments D have squared flat rear ends which butt up squarely against the front end of the tubular bearing A', and lack the hook and mortise connection with the front portion of said tubular bearing usually found in this type of expander. I come now to a description of that portion of the implement in which my improvement is more particularly comprised, and which is designed, as before said, to prevent the segment and coupling from moving forward with the mandrel after the copper coupling ring has been duly expanded into place, and to thus permit the ready removal of the coupling from the expander after the completion of the operation. The device I employ for the purpose is a chain, or its equivalent, secured at one end to the stand on one side thereof adjoining the front end of the tubular bearing in which the mandrel moves, and provided with means on the other side of the stand to secure the free end of the chain after the latter has been engaged with and drawn around the hose coupling so as to hold it in place upon the segments and up against the front end of the tubular bearing. In the preferred arrangement for this purpose, as shown in the drawings, the chain E is a flat chain having enlargements or knuckles at the points where the links are jointed together, said chain being connected to the stand by a pin f secured in ears g, laterally projecting from one side of the tubular mandrel bearing A', on which pin one end of the chain is hung. On the opposite side of the piece A' are two laterally projecting lugs h, the interval between which forms a slot i wide enough to permit the passage of the flat portion of the links between the knuckle joints, but not wide enough to receive the knuckles themselves. Thus when the flat part of one of the links is slipped from the front into the slot i, the knuckles on each side thereof will bring up against the lugs h, and will thus constitute dogs or stops to prevent longitudinal movement of the chain in either direction through said slot.

The manner of using the device is as follows: The copper coupling ring y is first placed on the segments, and then the coupling X containing the end of the hose m is placed over the mandrel and upon the

segments, and butting up against the usual annular flange v on the front end of bearing A', to bring the copper ring y opposite to the recess into which it is to be expanded, so as to force and clamp therein the hose. The expanding mandrel is then moved in a direction to draw its conical expanding portion toward the segments, thus expanding the ring y, and securing the hose to the coupling. Either before or after this operation, the holding chain is engaged with the coupling, and its free end is fastened in place. For this purpose it is first passed over the coupling lug x on one side of the coupling, down under and partly around the coupling, up to the coupling lug x on the opposite side of the coupling, over which lug it is drawn taut and then passed to the slot i which it engages by having the flat part of one of the chain links at its free end entered into said slot, as shown more particularly in Fig. 1, the knuckles at each end of the link bringing up against the faces of lugs h, and holding the free end of the chain tight against lengthwise movement. In order to release the hose coupling from the expander, the mandrel is moved to the front. Were it not for the chain, the segments and coupling ring, which by the expanding operation have become tightly wedged and stuck together and to the conical portion of the mandrel, would follow the movement of the mandrel and remain stuck thereon. But the chain holds the coupling fast against this movement, with the result that the segments and the coupling thereon, break away from the mandrel, and the segments thus loosened permit the ready detachment and removal of the coupling from the expander. The device can be used safely and readily by inexpert labor upon hose couplings of various sizes and forms. The chain may be passed around the coupling lugs x in any convenient manner, or, if there are no such lugs, may pass around the coupling itself, or even the hose itself just beyond the end of the coupling. Instead of a chain, I may use a rope, or other pliable member, provided at intervals with projections or enlargements corresponding in position and function to the knuckles or enlargements of the chain already described. Other fastening means for the free ends of the pliable coupling holding member may also be provided, in lieu of the particular means for this purpose herein illustrated, although the latter is the preferred form of such means.

What I claim herein as new and desire to secure by Letters Patent, is:

In a machine for expanding the holding ring used in fastening hose couplings upon hydraulic or other hose, and in combination with the expanding mandrel, mandrel supporting stand and actuating mechanism, and

the segments mounted upon said mandrel to receive said holding ring, a pliable retaining member, secured at one end to the mandrel supporting stand, and adapted to detachably engage the hose coupling operated on by the machine, and fastening means for securing against movement the free end of said pliable member thus engaged with the hose coupling, so as to hold the latter tightly in place against movement of the mandrel

5 in a direction to carry its conical expanding portion away from the segments, substantially as and for the purposes hereinbefore set forth.

10 In testimony whereof I affix my signature 15 in presence of two witnesses.

WILLIAM HENRY DAVIS.
